UNITED STATES PATENT OFFICE.

GRAFTON GREENOUGH, OF PHILADELPHIA, PENNSYLVANIA, ASSIGNOR, BY MESNE ASSIGNMENTS, TO LOCOMOTIVE SUPERHEATER COMPANY, A CORPORATION OF NEW JERSEY.

REHEATER FOR LOCOMOTIVES.

1,057,727.

Specification of Letters Patent.

Patented Apr. 1, 1913.

Application filed February 5, 1910. Serial No. 542,226.

To all whom it may concern:

Be it known that I, GRAFTON GREENOUGH, a citizen of the United States, residing in Philadelphia, Pennsylvania, have invented 5 certain Improvements in Reheaters for Locomotives, of which the following is a specification.

My invention relates to certain improvements in compound locomotives in which 10 the steam passes from a high pressure cylinder to a low pressure cylinder through a length of pipe.

The invention is particularly adapted for use in compound locomotives where the high 15 pressure cylinder is located at some distance from the low pressure cylinder.

The main object of the invention is to provide a re-heater for the steam as it passes from the high pressure cylinders to the low 20 pressure cylinders.

A further object of the invention is to so construct the heater that it can be mounted in the feed water section of the boiler.

In the accompanying drawings:—Figure 25 1, is a diagrammatic sectional view of sufficient of a locomotive boiler to illustrate my invention; Fig. 2, is a longitudinal sectional view on the line 2—2, Fig. 3, of sufficient of the boiler to illustrate my invention; Fig. 3, 30 is a transverse sectional view on the line 3—3, Fig. 2; Figs. 4 and 5, are views illustrating modifications of the invention.

A is a locomotive boiler having a steam section A' and the feed water section A², 35 separated by an intervening combustion chamber B. B' is the fire chamber and B² is the smoke box. This type of boiler is made in two sections coupled at a, and in the steam section A' are tubes a', and in the feed water section are tubes a². The high pressure cylinder is indicated at C by dotted lines, and the low pressure cylinder at C' by dotted lines, and my invention relates particularly to the re-heater through which 40 45 steam must pass which is exhausted from the high pressure cylinders and flows through the re-heater to the low pressure cylinder.

D is the re-heater, made cylindrical in the 50 present instance, the casing d of the re-heater extending beyond the tube sheets b, b' of the feed water heater a sufficient distance to allow the pipes c, c' respectively to be coupled to the re-heater outside of the feed water heater. The re-heater has head-

ers d', and extending from one header to the other within the heater is a series of flue tubes e. The flue tubes are open at the rear end to the intermediate combustion chamber B and at the forward end to the smoke box B². In the present instance c², c² are saddles secured to the projecting portions of the re-heater D, these saddles are coupled to the pipes c, c', as clearly shown. It will be noticed that there is a casing F secured to the two tube sheets b, b', and this casing is greater in diameter than the re-heater and the re-heater passes entirely through the casing. The space between the casing and the re-heater is open at both ends, 70 so as to allow for the free flow of the products of combustion through this space as well as through the tubes of the re-heater. This construction prevents the water in the feed water section coming in direct contact with the re-heater. Blocks f', or other suitable spacing means, may be used to properly support and space the re-heater, or a construction as shown in Fig. 4 may be used, 75 in which the casing F' is reduced in diameter at each end f² so as to fit the re-heater. This casing is not attached to the re-heater, and thus allows free expansion and contraction.

In Fig. 5, I have shown another method 80 of coupling the pipes c, c' to the re-heater D, and in this case the saddle is dispensed with and a plate c³ is used on the inside of the re-heater and is riveted to its shell, and the pipe c⁴ has a threaded portion which is 85 screwed into this plate.

By the above construction it will be seen that I make a very simple and effective re-heater for use in connection with the type of locomotive above described; the steam 90 has a free flow through the re-heater from the high pressure cylinder to the low pressure cylinder, and the products of combustion will readily pass through the tubes and through the space between the re-heater and the casing, as well as through the tubes of the feed water heater. When repairs are necessary the re-heater can be readily uncoupled and removed from the boiler and replaced.

I claim:—

1. The combination in a locomotive boiler, of a boiler section; a feed water section having a cylindrical opening extending entire therethrough; and a re-heater mounted in 110

- the said opening and projecting at each end into the intermediate combustion chamber and smoke box of the locomotive, whereby the products of combustion, passing through 5 the boiler, will pass through the feed water heater and the re-heater.
2. The combination of a boiler having a steam space; a feed water heater located beyond the steam space in the boiler and consisting of headers with longitudinal tubes therein; and a cylindrical casing, also attached to the headers; with a re-heater located within said casing and consisting of a casing and a series of longitudinally arranged flue tubes, so that the products of combustion, as they pass through the boiler, travel through the tubes of both the feed water heater and the re-heater.
3. The combination in a locomotive boiler 20 having a steam section at one end and a feed water section at the other end separated by an intervening combustion chamber; a fire box and a smoke box; tubes in the steam section through which the products of combustion pass from the fire box into the intermediate chamber; and a series of tubes in the feed water section; of an enlarged casing longitudinally arranged in the feed water section; a re-heater consisting of 25 a casing less in diameter than the casing in the feed water section and having a series of flue tubes therein so as to allow for the free passage of the products of combustion from the intermediate combustion chamber 30 through the flues of the feed water heater and the re-heater, said re-heater extending at each end beyond the feed water heater; and pipe connections on the extensions.
4. The combination in a locomotive boiler, 40 of a water containing section having tube sheets, flues extending from tube sheet to tube sheet through the water containing space, and an enlarged flue or casing also extending from tube sheet to tube sheet through the water containing space, a re-heater comprising a casing of smaller diameter than said first mentioned casing and supported within said casing with a space between the casings, tube sheets closing the ends of the last mentioned casing and flues extending from one of said last mentioned tube sheets to the other, whereby products of combustion may pass through said last mentioned tubes and through the space between said casings, 45 means to deliver steam to the space within the last mentioned casing around the last mentioned tubes and means to conduct steam from said space.
5. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 60
6. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 65
7. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 70
8. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 75
9. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 80
10. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 85
11. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 90
12. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 95
13. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 100
14. The combination in a locomotive boiler, of a boiler section, a feed water section having an enlarged flue or casing extending therethrough, a combustion chamber between the boiler section and the feed water section, a smoke box beyond the feed water section, and a re-heater mounted within said enlarged flue or casing and out of contact therewith, whereby the products of combustion, in their passage from the combustion chamber to the smoke box, pass through said enlarged flue or casing around the re-heater. 105

In testimony whereof, I have signed my name to this specification, in the presence of 110 two subscribing witnesses.
